(57) **CLAIM**

The ornamental design for a lid for tumbler or jar, as shown and described.

DESCRIPTION

FIG. 1 is a perspective view of a lid for tumbler or jar showing my new design.

FIG. 2 is top, plan view thereof.

FIG. 3 is a side elevation view thereof. The lid design is axially symmetrical and side elevation views from all directions are identical to FIG. 3.

FIG. 4 is a bottom view thereof.

FIG. 5 is a view in section, taken along the line 5—5 of FIG. 4, revealing a side view of the interior thereof including circumferentially spaced legs spaced radially inwardly from the periphery of the lid. All of the circumferentially spaced legs are identically configured; and,

FIG. 6 is a view in section, taken along the line 6—6 of FIG. 4, revealing a side view of a circumferentially spaced leg viewed from radially outwardly of the upstanding leg.
